US0D1093299S

(12) **United States Design Patent** (10) Patent No.: **US D1,093,299 S**
(45) Date of Patent: ** Sep. 16, 2025

(54) **MOBILE POWER DEVICE**

(71) Applicant: **Ugreen Group Limited**, Shenzhen (CN)

(72) Inventors: **Qingsen Zhang**, Shenzhen (CN); **Junling Chen**, Shenzhen (CN); **Houling Wang**, Shenzhen (CN)

(73) Assignee: **Ugreen Group Limited**, Shenzhen (CN)

(**) Term: **15 Years**

(21) Appl. No.: **29/905,753**

(22) Filed: **Oct. 25, 2023**

(51) LOC (15) Cl. **13-02**

(52) U.S. Cl.

USPC **D13/108**

(57)

CLAIM

The ornamental design for a mobile power device as shown and described.

DESCRIPTION

FIG. 1 is a front, right and top perspective view of a mobile power device showing our design.

FIG. 2 is a rear, left and bottom perspective view thereof.

FIG. 3 is a front elevation view thereof.

FIG. 4 is a rear elevation view thereof.

FIG. 5 is a left-side elevation view thereof.

FIG. 6 is a right-side elevation view thereof.

FIG. 7 is a top plan view thereof; and,

FIG. 8 is a bottom plan view thereof.

The broken lines are included for the purposes of illustrating portions of the mobile power device that form no part of the claimed design.

1 Claim, 8 Drawing Sheets
